(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

1.8 : Perspective

The design concerns a bracelet with a strap whose ends are connected by a clasp comprising a retaining mechanism carried by one end of the strap and a retaining member attached to the other end; the retained member has a diamond-shaped head and a rod that can be coupled to and retained by said mechanism; in the closed condition of the bracelet, the clasp as a whole has the appearance of a key.
